UNITED STATES PATENT OFFICE.

ORIN C. FENLASON, OF HOQUIAM, WASHINGTON.

COLLAPSIBLE VENEER BOX.

1,142,084.

Specification of Letters Patent.

Patented June 8, 1915.

Application filed January 10, 1914. Serial No. 811,380.

To all whom it may concern:

Be it known that I, ORIN C. FENLASON, a citizen of the United States, residing at Hoquiam, in the county of Chehalis and State of Washington, have invented a new and useful Collapsible Veneer Box, of which the following is a specification.

The invention relates to improvements in collapsible veneer boxes.

10 The object of the present invention is to improve the construction of collapsible veneer boxes, and to provide a simple, strong and efficient telescope box having a flat bottom to adapt it particularly for shipping merchandise by parcel post, and capable of being easily and quickly arranged for use and of being locked in such position for rigidly holding the box together.

20 A further object of the invention is to provide a box of this character adapted to be shipped in a flat knockdown or folded condition, thereby enabling the box to be shipped at a much lower rate than boxes made up or incapable of such compact folding.

25 It is also an object of the invention to provide a collapsible veneer box having a flat bottom composed of crossed strips of veneer, each providing a plurality of plies or thicknesses to form practically a tight bottom box.

30 With these and other objects in view, the invention consists in the construction and novel combination of parts hereinafter 35 fully described, illustrated in the accompanying drawings, and pointed out in the claim hereto appended; it being understood that various changes in the form, proportion, size and minor details of construction, 40 within the scope of the claim, may be resorted to without departing from the spirit or sacrificing any of the advantages of the invention.

45 In the drawings:—Figure 1 is a vertical sectional view of a collapsible veneer box, and cover, constructed in accordance with this invention. Fig. 2 is a perspective view of the box, the cover being removed and one corner of the box being broken away to 50 illustrate more clearly the arrangement of the bottom strip. Figs. 3 and 4 are perspective views, illustrating the manner of folding the collapsible box. Fig. 5 is a

similar view, the box being folded substantially flat. Fig. 6 is a perspective view of 55 a collapsible veneer box provided with a pair of bottom strips, the body of the box being collapsed and the strips being arranged in a straight parallel position. Fig. 7 is a perspective view of the box shown in 60 Fig. 6 arranged for use, one corner of the box being broken away to show clearly the double locking of the terminal portions of the bottom strips beneath the lower edges of the adjacent side walls. 65

Like numerals of reference designate corresponding parts in all the figures of the drawings.

In the accompanying drawings in which is illustrated the preferred embodiment of 70 the invention, the box is provided with a collapsible rectangular body 1 consisting of a single sheet or strip of veneer of sufficient length to form the four walls of the body and to provide overlapping terminals. A 75 strip or sheet of veneer is scored at the corners of the box, an extension 2 being provided at one end of the strip or sheet to overlap the other end portion, which is of sufficient length to form one of the side 80 walls of the box. The overlapped ends of the strip or sheet are pierced by the sides or legs of inclined staples 3, preferably two in number and located near the upper and lower edges of the body portion, but any 85 number of staples may be employed and the terminals of the strip or sheet may be secured together in any other suitable manner, if desired. The scoring of the veneer at the corners of the box enables the body to collapse or fold perfectly flat for shipping or storing. 90

The box is equipped with a foldable strip 4 scored at intervals to provide a terminal attaching portion 5, a lower or outer bottom 95 portion 6, outer and inner side embracing portions 7 and 8 and an inner or upper bottom portion 9, located at the free terminal of the strip and adapted to be interlocked with the body, as hereinafter fully 100 explained. The terminal attaching portion is secured by staples 10 to the outer face of one of the side walls of the body, preferably the wall adjacent to the extension 2, as clearly illustrated in Fig. 2 of the drawings, 105 and it preferably has its upper edge ar-

ranged in flush relation with the upper edge of the contiguous side wall and it extends downwardly below the lower edge of the same and is of a width slightly less than the 5 length of the said side wall to form a side wall of two plies or thicknesses. The lower or outer bottom portion 6 extends across the body to the opposite side wall thereof, which is arranged between and is embraced by the 10 portions 7 and 8. The outer side embracing portion 7 extends upwardly from the lower or outer bottom portion 6 of the strip 4 to the upper edge of the contiguous side wall of the body, and the inner side embracing 15 portion 8 extends downwardly at the inner face of such side wall of the body to the outer or lower bottom portion 6, thereby enabling the terminal portion 7, which constitutes the upper ply or thickness of the 20 bottom to be folded flat against the said lower or outer portion 6 and to be sprung under the lower edge of the side wall to which the terminal portion 5 of the strip is attached, thereby rigidly locking the parts 25 of the box together. This construction also forms a flat bottom of two plies or thicknesses and adapts the box for use in shipping merchandise by parcel post.

The box is equipped with a telescoping 30 cover 12 of the same construction as the box with the exception that it is made slightly larger to fit over the box to make a tight package, and as the cover is of the same construction of the body, a specific description 35 of the latter will afford a full and clear understanding of both structures. In folding the box, the rectangular body is collapsed, as indicated in Fig. 3 of the drawings, the bottom strip being straight. The bottom 40 strip is then folded at the scoring 13 to arrange the side embracing portion 8 over the corresponding side embracing portion 7 and the inner or upper bottom portion 9 over the lower bottom portion 6. The side 45 embracing portions 7 and 8 and the bottom portions 6 and 9 are of substantially the same size, the outer portion 7 being slightly longer than the inner portion 8, as clearly illustrated in Fig. 4 of the drawings, to permit 50 a second fold to be made for arranging the side embracing portions 7 and 8 upon the bottom forming portions 6 and 9. The collapsed body portion of the box is then folded at the scoring 14 to arrange it upon the 55 folded strip, as clearly shown in Fig. 5. In Fig. 5, the collapsed body is shown at a slight angle, and there is a slight space at the center in order to illustrate the construction more clearly, but in practice the 60 box will fold flat, as will be readily understood.

In arranging the box for use, the collapsible body portion is swung outwardly from over the folded strip, and the latter is un-

folded. The body portion is opened out 65 into true rectangular shape with the outer bottom portion 6 extending across the bottom of the said body portion. The outer side embracing portion 7 is then swung upwardly against the exterior of the adjacent 70 side of the body portion 1 and the inner side embracing portion is folded downwardly within the same, carrying with it the inner or upper bottom portion 9, which is pressed downwardly within the box and tucked under and engaged with the edge of the body portion. This rigidly locks the parts in position for use. The inner and outer side 75 engaging and embracing portions frictionally clamp the contiguous side wall of the body between them and they form with the same a side wall of three plies or thicknesses. The inner and outer bottom forming portions 6 and 9 provide a flat bottom of two plies or thicknesses, which adapt the box 80 particularly for shipping merchandise by parcel post. The arrangement of the bottom forming strip on the collapsed body in this manner provides a strong and durable structure as the wall of two plies or thicknesses at one side and the opposite wall of three plies or thicknesses and a connecting bottom portion of three plies or thicknesses. When, however, it is desired to construct a 85 box with a practically tight bottom, a pair of bottom strips 15 may be employed. The bottom strips 15 are scored at intervals and are of a length to form an attaching terminal portion 16, and a lower or outer bottom forming portion 17, outer and inner side 90 embracing portions 18 and 19 and an inner or upper bottom forming portion 20. When the collapsible rectangular body portion 21 is collapsed, as illustrated in Fig. 6 of the 95 drawings, the bottom forming strips are arranged in parallelism and the opening movement of the body portion 21 carries the strips to positions at right angles to each other. The strips are successively folded in the 100 same manner as the strip 4, and they form a flat bottom of four plies or thicknesses and provide practically a tight bottom.

What is claimed is:—

A collapsible or knock-down box including a rectangular collapsible body, and a bottom forming strip secured to one terminal of the body at one of the side walls thereof and scored at intervals to form a lower or outer bottom portion, inner and outer side embracing portions, and an inner or upper bottom portion, said strip extending from the wall to which it is attached to the opposite side wall and bent upward exteriorly thereof and folded over the upper edge of the same and extending downwardly at the 115 inner face of such side walls to the lower edge thereof, the free terminal portion of such strip extending across the body of the 120

inner face of such side walls to the lower edge thereof, the free terminal portion of such strip extending across the body of the 125

box and constituting an inner or upper bottom ply, and the free end of the latter being tucked under and engaged with the lower edge of the body at the side to which the strip is attached, whereby the strip is locked in position and the box held from collapsing.

5 In testimony, that I claim the foregoing

as my own I have hereto affixed my signature in the presence of two witnesses.

ORIN C. FENLASON.
